UNITED STATES PATENT OFFICE

JAMES MORTON, OF CRAMOND BRIDGE, WEST LOTHIAN, SCOTLAND

JACQUARD MECHANISM

Application filed October 27, 1930, Serial No. 491,431, and in Great Britain November 19, 1929.

It is well known to employ jacquard mechanism for the purpose of controlling the extent through which a plurality of carriers are moved so as, for instance, to bring ends of 5 yarns having different characteristics (e. g. different colours) into positions in which selected pieces or lengths of said yarns can be withdrawn for incorporation in a fabric.

The present invention relates to such mechanism, but of the particular type wherein only a fraction of the total number of rows of holes and blanks in each of the jacquard cards used is operative at each stroke of the card cylinder, and wherein the card cylinder 15 is moved bodily after each stroke so as to bring a new set of rows in the same card into the operative position.

The object of the invention is to provide jacquard mechanism of the above type which will be simpler and cheaper to construct than heretofore.

According to the invention, the improved mechanism comprises a card cylinder adapted to move up-and-down below a number of 20 groups of relatively movable vertical members, formed with co-operating recesses, and thereby actuate selected members of said groups, and horizontal wires adapted to control the carriers, said wires being associated with said members in such a manner that selected wires, when located in registering groups of said recesses, become operative on the carriers.

The horizontal wires, which are initially set or sprung so that they tend normally to enter the recesses, are preferably arranged in vertical rows and associated with an assembly of members which can be moved laterally to pull the horizontal wires clear of the recessed members.

Each group of recessed members may comprise an appropriate number of light slats, and these slats may be formed or provided 25 with card-engaging parts which are bent or set in pairs so that all these parts can be arranged in two long rows and therefore require only two rows of holes and blanks in the cards for their operation. This allows a 30 standard card of sixteen rows to be used for

eight successive strokes before bringing a new card into operation.

One form which the invention can take is illustrated, by way of example, in the accompanying drawings in which:—

Fig. 1 is an end elevation of the jacquard mechanism, parts thereof being omitted for clearness.

Fig. 2 is a sectional view of certain of the parts already shown in Fig. 1 and of other parts omitted therefrom.

Fig. 3 is a fragmentary sectional plan of the jacquard mechanism, parts thereof being removed for clearness.

Figs. 4 and 5, respectively, are fragmentary views showing details of construction.

Figs. 6 and 7 are elevations at right angles to one another of a group of slats constituting the above mentioned vertical recessed members.

The jacquard mechanism and associated parts are supported by a frame 10.

The carriers to be controlled by the jacquard mechanism each consist of a vertical bar 11 provided with a vertical row of eight stops, consisting of horizontal pins 12, these pins penetrating the bar transversely thereof and passing through an elongated slot 13 therein. At one side of the slot 13 a spring strip 14 is secured which is formed with tongues 15 projecting into the slot 13 and bearing against the respective pins 12 so as to impose a frictional drag thereon. The bars 11 are guided top and bottom by pairs of co-operating plates 16 and 17 supported respectively by the frame 10 and brackets 18 thereon, the bars passing through slots in these plates. Each bar at its top end is formed with a shoulder 19 which normally rests upon the topmost plates 16, 17, thus supporting the bar as a whole. The pins 12 are individually slidable across the bars into an operative position or an inoperative position (in which they are shown in the drawings) and are normally maintained in either position by the frictional action of the tongues 15.

The carriers constituted by the bars 11 co-operate with a vertically reciprocable horizontal bar, or "straight-edge", 20 which is so

disposed that, when it is lifted, it would engage, in each carrier, with a pin 12 which, for the time being, should occupy its operative position, in which it would project into the path of the bar 20. The bar 20 is supported at each end by a block 21 secured to a slide rod 22. The bar 20 derives its vertically reciprocating motion from a swinging arm 23 secured to a rock-shaft 24 and connected 10 by a link 25 to a block 26 secured to the slide rod 22. Each carrier 11 would have attached to its lower end a member (not shown) presenting, for example, a vertical row of differently coloured threads. The arrangement 15 would thus be such that, whenever each carrier should be lifted to a certain extent by the rising bar 20, during each cycle of operations of the jacquard, it would carry the member with it, and the latter would thereby 20 bring a selected one of the coloured threads into a position in which it could be engaged by grippers for ultimate incorporation in the fabric being manufactured.

The jacquard proper comprises a large 25 number of horizontal wires 30, groups of vertical slats 31, three assemblies 32, 33 and 34 respectively of vertical rods and a somewhat similar assembly of angle bars 35, called hereinafter a grid (see Figs. 2 and 3).

30 The horizontal wires 30, like the pins 12 on the carriers 11, are arranged in vertical rows, there being one wire for each pin 12. At the end of each wire adjacent to the respective pin, a loop 30^a is formed through 35 which passes one of a large number of vertical blades 36 supported by a rigid frame 37. These blades serve as limit stops, or "keepers", for positioning the wires. In the vicinity of the slats 31, the wires are formed with 40 flats 30^b. The wires 30 are supported near their ends by vertical rows of horizontal rods 38 and 39 respectively mounted in frames 40 and 41. Springs 42 are wound around the 45 loops 30^a, the springs pressing at one end against the blades 36 and at the other end being secured to the loop 30^a. Normally, the flats 30^b of the wires 30 press against the slats 31 and tend to enter recesses therein, said recesses being hereinafter described.

50 The assemblies of rods 32 and 33, which are respectively mounted in frames 43 and 44, are provided for the purpose of setting or springing the wires 30 towards the slats 31. The extent to which the wires are set or 55 sprung towards the slats can be regulated by adjusting the frame 44 appropriately. In order that such adjustment can be effected, there is provided at each end of the frame 44 a fixed bracket 45 through which a set screw 46 is threaded, the said screw 46 pressing 60 against the adjacent end of the frame (see Fig. 3).

The third assembly of rods 34 is mounted on a horizontally movable frame 47, which is supported at each end by a fixed bracket 48.

At one end, as shown in Fig. 4, the frame 47 has an arm 49 which is secured to one arm 50 of a bell-crank-lever 50, 51 fulcrumed on a fixed bracket 52. The other arm 51 of the bell-crank-lever is operatively connected to mechanism actuated by a cam which is actuated in its turn by the mechanism (not shown) of the loom. The arrangement is such that, when the arm 51 is lowered by the cam-mechanism, each rod 34 pulls a vertical row of wires 30 clear of the respective slats 31. When, on the other hand, the arm 51 is raised by the cam-mechanism, the wires 30 are allowed to move back against the slats 31 so that they tend to enter the recesses therein.

70 As shown in Figs. 6 and 7, the slats 31 are formed with specially shaped recesses or notches 31^a, which are indicated by vertical shade lines in Fig. 6.

75 The slats 31 are provided top and bottom with extensions 31^b and 31^c, respectively, which extensions are individually guided through fixed bars 60 and 61, the limits of the movement of each group of slats being defined by a fixed pin 62 passing through 80 registering slots 63 in the respective group of slats. The slats are urged continuously downwards by springs 64 interposed between the bars 60 and collars 65 on the extensions 31^b. The extensions 31^b and 31^c are twisted 85 so that they are respectively disposed in two parallel rows.

90 The jacquard card-cylinder 66, which as shown in Fig. 2 is disposed beneath the two rows of extensions 31^c, is associated with mechanism (hereinafter described) whereby the cylinder is traversed step-by-step across the extensions. At each step of the cylinder, which takes place after each vertical stroke thereof, two new rows of holes and blanks in the card C on top of the cylinder are brought into register with the two rows of extensions 31^c. During each vertical stroke of the cylinder 66, the card C moves into operative relationship with the extensions 31^c, certain or none of which may 100 be raised in accordance with the arrangement of the holes and blanks in the card C. If no extension 31^c in any group of slats 31 is engaged and raised, then the position will 105 be the same as illustrated in Figs. 6 and 7, in which it will be observed that the lowermost recesses of all the slats register in a position in which they can be entered by the lowermost flat 30^b of the respective vertical row of wires 30. It will be apparent that, if one or more of the slats were to be raised, a different recess would be provided for one of the other wires.

110 The stack of slats shown in Figs. 6 and 7 is capable of forming recesses at sixteen different levels, but only eight of these levels are of use in the particular arrangement of jacquard mechanism shown, since such mechanism is adapted to control carriers having 115 120 125 130

a range of only eight selectors. However, if desired, the slats shown could be embodied in a jacquard giving a range of sixteen selections, instead of merely eight.

5 The above-mentioned grid constituted by the assembly of angle bars 35 is adapted to be reciprocated horizontally towards and away from the adjacent ends of the wires. The arrangement is such that, if any wire should 10 have entered a set of registering recesses, its end will be engaged by one of the grid bars and the respective wire will be moved so as to engage the respective pin 12 and move the latter into its operative position.

15 The bars 35 are set in a frame 70 which is secured at each end to a slide rod 71 supported by bearings 72 on the frame 10. The frame 70 derives its reciprocating movements from a rock-shaft 73 having at each 20 end a crank 74 coupled by a link 75 to a block 76 secured to the rod 71.

In order to reduce the number of bars 35 to a minimum so that the bars will be adequately spaced, every alternate vertical row 25 of wires 30 is cranked at 30° so as to bring the ends of these cranked wires into the same vertical row as the corresponding ends of the adjacent vertical row of wires.

At the side of the frame 10 at which the 30 carriers 11 are mounted, there is provided a board or plate 80 supported at its ends by arms 81 secured to a rock shaft 82. The board 80 is arranged to be swung against the pins at the end of each cycle of operations 35 and thereby moves such pins as may occupy their operative position into their inoperative position.

The mechanism for operating the card-cylinder 66 will now be described.

40 The cylinder 66 is mounted on a shaft 90. Each end of this shaft passes into a slideway 91 in a vertically reciprocatory bar 92 provided with an upright slide rod 93 passing through bearings 94 on the frame 10. The 45 vertical reciprocations of the bar 92 are derived from a rock-shaft 95 having at each end a crank 96 coupled by a link 97 to a block 98 secured to the rod 93. The weight of the bar 92 and the parts carried thereby is taken in 50 some measure by a strong spring 99, one end of which is anchored at 99^a to the frame 10 and the other end of which is attached to a hook 99^b on the base of the rod 93. The arrangement of the above mechanism is such 55 that the bar 92 receives one vertical reciprocation in each cycle of operations, during which reciprocation the cylinder 66 is moved against the extensions 31^c, and certain (or possibly none) of these are raised in accordance with the arrangement of holes and 60 blanks in the card C.

The mechanism for imparting step-by-step lateral movements to the card-cylinder includes a cam 100 on a shaft 101 journalled in 65 the bar 92. The cam 100 has for its follower

a roller 102 on the shaft 90, the roller 102 being held against the profile of the cam 100 by a spring 103, one end of which is anchored at 103^a to the frame 10 and the other end of which is attached to a pin 103^b on a part 116 70 associated with the card-cylinder. The cam 100 is actuated by a wheel 104 which is secured to the shaft 101 and which is provided with eight circularly arranged pins 104^a co-operating with a hook or "snick" 105 pivotally attached at its stop end to the frame 10. The pins 104^a also co-operate with a detent lever or "stamper" 106 which is pivotally attached at one end to the bar 92 and which is 75 attached at its other end to the opposite end of the bar 92 by a spring 107. During each cycle of operations of the above mechanism, one of the pins 104^a is engaged by the hook 105 during the downward movement of the bar 92, with the result that the wheel 104 and cam 100 are turned through an eighth of a revolution, and are held in place by the spring-urged lever 106. In consequence, the follower 90 together with the cylinder 66 are moved one step to the right, thereby bringing 80 two new rows of blanks and holes in the card C into register with the extensions 31^c.

The card-cylinder 66 is provided at each end with the usual lantern 110, which co-operates with a spring-pressed hammer 111 85 for holding the cylinder properly positioned. Both the hammer and its spring, which is denoted by 112, are mounted in the usual manner in a fitting 113, which is attached to a slide-block 114 movable in the slide-way 91 90 and attached by parts 115, 116 to the shaft 90.

The parts of the mechanism above described are all shown located at one end of the jacquard mechanism. It will be readily understood that, where necessary, these parts will be duplicated at the other side of the mechanism.

With reference to Fig. 5, the parts therein shown are located at the far side of the jacquard mechanism. The device illustrated in Fig. 5 is provided for the purpose of turning the card-cylinder 66 counter-clockwise through 90° at the end of its lateral traverse to the right in order to bring a new card C¹ 105 into the operative position. The device shown comprises a hook 121 pivotally attached at its top end to the frame 10. The hook is provided with a set screw 122 adapted to rest against an abutment 123 on the frame 10, the screw being pressed against 110 the abutment by a weight 124. By adjusting the set screw 122, the hook can be set correctly in a position in which it will co-operate with the lantern 110 of the card cylinder when the latter has moved into its extreme 115 right hand position. The weight 124 is adjustably secured to a rod 125 extending from the hook 121 and co-operates with a striker 126 adjustably attached to the fitting 113 on the bar 92. The arrangement is such that, 120 125 130

as the cylinder 66 approaches its right hand position, the striker 126 engages the arm 125 during each upstroke of the card-cylinder, thereby moving the hook 121 clear of the lantern 110. When, however, the card-cylinder moves into its extreme right hand position the striker 126 misses the arm 125, with the result that the hook 121 co-operates with the lantern 110 and imparts thereto and to the cylinder a movement of 90° in the counterclockwise direction on the next down stroke.

In the operation of the jacquard, the assembly of vertical rods 34 is maintained so positioned by the cam-mechanism as to keep the wires 30 clear of the slats 31. The card-cylinder 66 is raised by the shaft 95 and intermediate mechanism and presses up certain, or all, or none, of the slats of each group, and this brings, or leaves, one set of recesses 31^a in register. The rods 34 are now returned horizontally so as to allow the wires 30 to spring against the slats 31, one wire (i. e. the selected wire) of each vertical row entering the registering recesses. The grid is now moved towards the wires, and the bars 35 thereof engage with all those which have been selected. These wires engage with the corresponding carrier pins 12 and move them into their operative position in the path of the horizontal bar 20. The bar 20 now lifts and engages the selected pins 12, thus raising the carriers 11 through part of its upward travel.

Thereafter, the bar is lowered, all the carriers coming to rest in their lowermost position, the grid is withdrawn from the wires, which accordingly spring back endwise to their normal position, and the rods 34 are moved to pull the wires sidewise clear of the slats, whereupon the card-cylinder is lowered and the raised slats spring downwards therewith. In addition, the board or plate 80 swings forward and presses the displaced carrier pins back into their inoperative position ready for the next cycle of operations.

The card-cylinder, after the completion of its stroke, is next traversed by the cam 100 across the slat extensions so as to bring two new rows of card holes and blanks into operative relationship therewith. The above cycle of operations is once more repeated.

The above cycle of operations takes place eight times for each card, there being eight pairs of holes and blanks therein. Thereafter, the hook 121 turns the card-cylinder to bring a new card into operation, and the cam 100 allows the cylinder to move back laterally to its starting position, in which the slat extensions 31^a register with the first pair of rows of holes and blanks.

Although it has been stated that jacquard mechanism according to this invention is suitable for use with members adapted to supply thread to grippers, for instance in a grip-

per loom, it is to be understood that the invention is not limited to such use.

It is further to be understood that modifications in the details of construction and arrangement can be made without departing from the scope of the invention.

I claim:—

1. Jacquard mechanism of the type specified for controlling a number of carriers, said mechanism comprising horizontal wires movable endwise to co-operate with parts on the carriers, groups of relatively movable vertical members for rendering selected wires operative, mutually co-operating recesses in said members, a vertically reciprocating card cylinder mounted below said vertical members and adapted to actuate selected members in the several groups, and means for moving each selected wire endwise.

2. Jacquard mechanism of the type specified for controlling a number of carriers, said mechanism comprising horizontal wires co-operating with parts on the carriers, said wires being movable sidewise into operative and inoperative positions and being movable endwise to actuate said parts, groups of relatively movable vertical members for rendering selected wires operative, mutually co-operating recesses in said members, a vertically reciprocating card cylinder mounted below said vertical members and adapted to actuate selected members in the several groups, and means for moving each selected wire endwise.

3. Jacquard mechanism of the type specified for controlling a number of carriers, said mechanism comprising horizontal wires co-operating with parts on the carriers, said wires being movable endwise to actuate said parts, groups of relatively movable vertical members having mutually co-operating recesses which when in register are entered by a selected horizontal wire, the wire thus becoming operative, a vertically reciprocating card cylinder mounted below said vertical members and adapted to actuate selected members in the several groups so as to bring corresponding recesses into register, and means for moving each selected wire endwise.

4. Jacquard mechanism of the type specified for controlling a number of carriers, said mechanism comprising horizontal wires movable endwise to co-operate with parts on the carriage, groups of relatively movable vertical members having mutually co-operating recesses, positioning means normally urging said wires towards said members, a vertically reciprocating card cylinder mounted below said vertical members and adapted to actuate selected members in the several groups so as to bring corresponding recesses into register, a selected wire thus entering a set of registering recesses in each

group of members, and means for moving each selected wire endwise.

5. Jacquard mechanism of the type specified for controlling a number of carriers, said mechanism comprising horizontal wires movable endwise to co-operate with parts on the carriers, said wires being arranged in vertical rows, groups of relatively movable vertical members, mutually co-operating recesses in said members, setting means acting on said wires so that they tend to enter registering recesses, a vertically reciprocatory card cylinder mounted below said vertical members and adapted to actuate selected members in the several groups so as to bring corresponding recesses in each group into register, means for moving endwise the horizontal wires that enter the registering recesses, spring means for returning said wires, and an assembly of members for pressing the several vertical rows of wires clear of the vertical members at timed intervals.

6. Jacquard mechanism of the type specified for controlling a number of carriers, said mechanism comprising horizontal wires movable endwise to co-operate with parts on the carriers, groups of relatively movable vertical members for rendering selected wires operative, mutually co-operating recesses in said members, lower ends on said members arranged in a pair of rows, a vertically reciprocatory card cylinder mounted below said vertical members, said cylinder being arranged to receive cards having a number of pairs of rows of holes and blanks to co-operate with said lower ends, means for moving each selected wire endwise, and means for moving said cylinder a step sidewise in the interval between its vertical reciprocations.

40 7. Jacquard mechanism of the type specified for controlling a number of carriers, said mechanism comprising horizontal wires co-operating with parts on the carriers, said wires being movable endwise to actuate said parts, groups of relatively movable vertical members having mutually co-operating recesses which when in register are entered by a selected horizontal wire, the wire thus becoming operative, lower ends on said members arranged in a pair of rows, a vertically reciprocatory card cylinder mounted below said vertical members, said cylinders being arranged to receive cards having a number of pairs of rows of holes and blanks to co-operate with said lower ends so as to bring corresponding recesses in each group into register, means for moving each selected wire endwise, and means for moving said cylinder a step sidewise in the interval between its vertical reciprocations.

8. Jacquard mechanism of the type specified for controlling a number of carriers, said mechanism comprising horizontal wires movable endwise to co-operate with parts on the carriage, groups of relatively movable ver-

tical members having mutually co-operating recesses, lower ends on said members arranged in a pair of rows, positioning means normally urging said wires towards said members, a vertically reciprocatory card cylinder mounted below said vertical members, said cylinder being arranged to receive cards having a number of pairs of rows of holes and blanks to co-operate with said lower ends so as to bring corresponding recesses in each group into register, a selected wire thus entering a set of registering recesses in each group of members, means for moving each selected wire endwise, and means for moving said cylinder a step sidewise in the interval between its vertical reciprocations.

9. Jacquard mechanism of the type specified for controlling a number of carriers, said mechanism comprising horizontal wires movable endwise to co-operate with parts on the carriers, said wires being arranged in vertical rows, groups of relatively movable vertical members, mutually co-operating recesses in said members, lower ends on said members arranged in a pair of rows, setting means acting sidewise on said wires so that they tend to enter registering recesses, a vertically reciprocatory card cylinder mounted below said vertical members, said cylinder being arranged to receive cards having a number of pairs of rows of holes and blanks to co-operate with said lower ends so as to bring corresponding recesses in each group into register, means for moving endwise the horizontal wires that enter the registering recesses, spring means for returning the wires thus moved, an assembly of members for pressing the several vertical rows of wires clear of the vertical members at timed intervals, and means for moving said cylinder a step sidewise in the interval between its vertical reciprocations.

10. Jacquard mechanism of the type specified for controlling a number of carriers, said mechanism comprising horizontal wires movable endwise to co-operate with parts on the carriers, groups of relatively movable vertical members for rendering selected wires operative, mutually co-operating recesses in said members, a vertically reciprocatory card cylinder mounted below said vertical members and adapted to actuate selected members in the several groups, a grid of bars arranged in alignment with the selected bars, and means for reciprocating said grid to move the selected bars endwise to actuate said parts.

11. Jacquard mechanism of the type specified for controlling a number of carriers, said mechanism comprising horizontal wires movable endwise to co-operate with parts on the carriers, groups of relatively movable vertical members for rendering selected wires operative, mutually co-operating recesses in said members, lower ends on said members arranged in a pair of rows, a vertically recipro-

catory card cylinder mounted below said vertical members, said cylinder being arranged to receive cards having a number of pairs of rows and blanks to co-operate with said lower ends, a grid of bars arranged in alignment with the selected bars, and means for reciprocating said grid to move the selected bars endwise to actuate said parts.

12. Jacquard mechanism of the type specified for controlling a number of carriers, said mechanism comprising horizontal wires movable endwise to co-operate with parts on the carriers, said wires being arranged in vertical rows, groups of relatively movable vertical members, mutually co-operating recesses in said members, lower ends on said members arranged in a pair of rows, setting means acting sidewise on said wires so that they tend to enter registering recesses, a vertically reciprocatory card cylinder mounted below said vertical members, said cylinder being arranged to receive cards having a number of pairs of rows and blanks to co-operate with said lower ends so as to bring corresponding recesses in each group into register, a grid of vertical bars arranged in alignment with the horizontal wires that enter the registering recesses, means for reciprocating said grid to move the last mentioned wires endwise, spring means for returning the wires thus moved, an assembly of members for pressing the several vertical rows of wires clear of the vertical members at timed intervals, and means for moving said cylinder a step sideways in the interval between its vertical reciprocations.

13. Jacquard mechanism of the type specified for controlling a number of carriers, said mechanism comprising horizontal wires movable endwise to co-operate with parts on the carriers, said wires being arranged in pairs of vertical rows, the wires in each pair of rows having their ends set in a single row, groups of relatively movable vertical members, mutually co-operating recesses in said members, setting means acting on said wires so that the wires tend to enter registering recesses, a vertically reciprocatory card cylinder mounted below said vertical members and adapted to actuate selected members in the several groups so as to bring corresponding recesses in each group into register, a grid of vertical bars arranged in alignment with the horizontal wires that enter the registering recesses, means for reciprocating said grid to move the last mentioned wires endwise, spring means for returning the wires thus moved, and an assembly of members for pressing the several vertical rows of wires clear of the vertical members at timed intervals.

14. Jacquard mechanism of the type specified for controlling a number of carriers, said mechanism comprising horizontal wires movable endwise to co-operate with parts on the carriage, groups of relatively movable ver-

tical members having mutually co-operating recesses, relatively adjustable assemblies of rods which serve to spring the horizontal wires towards the respective groups of recessed members, a vertically reciprocatory card cylinder mounted below said vertical members and adapted to actuate selected members in the several groups so as to bring corresponding recesses into register, a selected wire thus entering a set of registering recesses in each group of members, and means for moving each selected wire endwise.

15. Jacquard mechanism of the type specified for controlling a number of carriers, said mechanism comprising horizontal wires movable endwise to co-operate with parts on the carriers, said wires being arranged in pairs of vertical rows, the wires in each pair of rows having their ends set in a single vertical row, groups of relatively movable vertical members, mutually co-operating recesses in said members, relatively adjustable assemblies of rods which serve to spring the horizontal wires towards the respective groups of recessed members so that the wires tend to enter registering recesses, a vertically reciprocatory card cylinder mounted below said vertical groups so as to bring corresponding recesses in each group into register, a grid of vertical bars arranged in alignment with the horizontal wires that enter the registering recesses, means for reciprocating said grid to move the last mentioned wires endwise, spring means for returning the wires thus moved, and an assembly of members for pressing the several vertical rows of wires clear of the vertical members at timed intervals.

16. Jacquard mechanism of the type specified for controlling a number of carriers, comprising horizontal wires co-operating with parts on the carriers, flat portions on said wires, groups of relatively movable vertical members, mutually co-operating recesses in said members, a vertically reciprocatory card cylinder mounted below said vertical members and adapted to actuate the members of the several groups so as to bring corresponding recesses into register, means urging said wires towards said members so that the flat portions of selected wires enter the registering recesses, and means for moving the last mentioned wires endwise to actuate the said carrier parts.

17. Jacquard mechanism of the type specified for controlling a number of carriers, said mechanism comprising horizontal wires movable endwise to co-operate with parts on the carriers, said wires being arranged in vertical rows, flat portions on said wires, groups of relatively movable vertical members, mutually co-operating recesses in said members, lower ends on said members arranged in a pair of rows, setting means acting sidewise on said wires so that their flat portions tend

to enter registering recesses, a vertically reciprocating card cylinder mounted below said vertical members, said cylinder being arranged to receive cards having a number 5 of pairs of rows and blanks to co-operate with said lower ends so as to bring corresponding recesses in each group into register, means for moving endwise the horizontal wires whose flat portions enter the registering recesses, spring means for returning the wires thus moved, an assembly of members for pressing the several vertical rows of wires clear of the vertical members at timed intervals, and means for moving said cylinder a 10 step sidewise in the interval between its vertical reciprocations.

18. Jacquard mechanism of the type specified comprising a number of carriers each having a range of movable stops, a like number 20 of vertical rows of horizontal wires for moving the stops relatively into an operative position, means for engaging one selected stop in each carrier in order to raise the carrier a determinate amount, groups of vertically 25 movable members associated with the respective rows of wires and formed with mutually co-operating recesses, a vertically movable cylinder for jacquard cards adapted as the cylinder is raised to engage selected members 30 and bring these into positions in which recesses in each group of members register with one another at the level of a selected wire to afford an opening for the accommodation thereof, and means for imparting endwise 35 movement to the selected wires, thereby rendering the corresponding stops operative.

In testimony whereof I affix my signature.
JAMES MORTON.
